UNITED STATES PATENT OFFICE.

HENRY L. HASKELL, OF LUDINGTON, MICHIGAN, ASSIGNOR TO HASKELITE MANUFACTURING CORPORATION, A CORPORATION OF NEW YORK.

HINGE.

1,309,730.

Specification of Letters Patent. Patented July 15, 1919.

Application filed August 9, 1918. Serial No. 249,076.

To all whom it may concern:

Be it known that I, HENRY L. HASKELL, a citizen of the United States, residing at Ludington, county of Mason, State of Michigan, have invented a certain new and useful Improvement in Hinges, and declare the following to be a full, clear, and exact description of the same, such as will enable others skilled in the art to which it pertains to make and use the same, reference being had to the accompanying drawings, which form a part of this specification.

My invention has for its object to produce a strong simple hinge for connecting together parts made of laminated wood veneer such as, for example, airplane members.

A further object of my invention is to produce a simple and novel hinge which will provide a substantially continuous unbroken surface on each side of two connected members in the various relative angular positions which the members are adapted to assume.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a top plan view of the tail of an airplane having the rudder and stabilizers attached by means of hinges embodying the present invention;

Fig. 2 is a side elevation of the extreme rear end of the airplane tail showing only the rudder and its hinge;

Fig. 3 is a section on an enlarged scale, on line 3—3 of Fig. 2;

Fig. 4 is a perspective view of a fragment of the rudder and a fragment of the post or support to which the rudder is hinged, the rudder being displaced a short distance from the support to show the construction of the hinge;

Fig. 5 is a transverse section through the hinge, on an enlarged scale, taken approximately on line 5—5 of Fig. 2;

Fig. 6 is a view similar to Fig. 5, showing the condition of the parts when the rudder is swung toward one side; and

Fig. 7 is a view similar to Fig. 5, showing a modification.

Referring to the drawings, 1 represents

the extreme rear end of the fuselage of an airplane, 2 is the rudder, and 3, 3 are stabilizers; the members 2 and 3 being hinged to swing about vertical and transverse axes, respectively. Since the present invention has to do particularly with the hinge, I shall describe it in detail only as constructed in connection with one of the hinge members, namely the rudder.

The rudder may conveniently be made of a single piece of laminated wood veneer folded or bent upon itself and the free edges, as indicated at 4, being brought together and fastened to each other in any suitable way. The bend or fold in the sheet of veneer is so made as to form a semi-cylindrical member of a diameter equal to the thickness that the rudder is to have at its front end. The stationary supporting part of a post, 5, is also made of a sheet of laminated wood-veneer bent into a form which provides a vertical semi-cylindrical part of the same diameter as the semi-cylindrical part of the rudder but having its convex side directed rearwardly whereas the convex side of the semi-cylindrical front edge of the rudder is directed forwardly. It will be seen that by removing sections at intervals from the cylindrical part of the rudder and removing from the post sections registering with the unimpaired portions of the rudder, two sets of hinge knuckles are produced which may be interlocked with each other and provided with a suitable pintle extending through the same. The hinge knuckles are possibly best shown in Fig. 4 where the parts marked 6 are the knuckles on the rudder and the parts marked 7 are the co-operating knuckles on the supporting member or post. The space within each hinge knuckle may be filled with a block as indicated at 8, provided with a small bore, 9, extending through the same for the reception of a pintle, 10. Where the hinges are of considerable length it may be desirable to form the holes 9 as the bottoms of slots, 11, cut through corresponding sides of the blocks, the slots being then partially closed by means of filling pieces, 12. By this arrangement it is unnecessary to drill long holes.

If desired, the hinge pintle may be formed out of a metal tube, 14, of the same external diameter as the internal diameter of the semi-cylindrical hinge knuckles, as indicated

in Fig. 7. Where this arrangement is employed the hinge knuckles may contain blocks, 15, having semi-cylindrical seats, 16, which form with the semi-cylindrical veneer 5 full cylindrical bearings for the pintle.

If the sections that are removed to produce the hinge knuckles are cut in deeply enough to permit the rudder to swing freely in the usual way, there would at all times 10 be passages or openings along the hinge on at least one side and sometimes on both sides. This would interfere with the free flow of air along the surfaces of the supporting member 5 to the corresponding surfaces of the rudder. To avoid this I make 15 the excisions no deeper than one-half of the diameter of the hinge knuckles so that when the parts are assembled the free edges, 17, of each hinge leaf engage with the sides of 20 the opposed knuckle members with which they register; the material of the leaves being preferably sharpened down to a feather edge as indicated at 18 so that there will be no abrupt shoulder or projections. This 25 arrangement would prevent the rudder from swinging and therefore I have cut slits a short distance into the hinge leaves at the ends of the knuckles, as indicated at 19, so that the tapered edges, 17, are, in fact, carried upon the ends of tongues, 20, which will yield as the rudder is swung to one 30 side or the other, as best shown in Fig. 6, and thus maintain a continuous unbroken surface from the front to the rear at both 35 sides of the joint between the rudder and the fuselage.

I desire to have it understood that my invention is not limited to the exact structural details illustrated and described; that it is 40 not limited to the particular use described herein or even to an embodiment in which the double leaves of each hinge are continued or extended to form a double-walled part to be supported or to form the support, 45 and that it is intended to include all forms and arrangements coming within the definitions of my invention constituting the appended claims.

I claim:

50 1. A hinge made of sheets of laminated wood veneer each folded so as to form two leaves connected by a semi-cylindrical member, sections of said semi-cylindrical members being removed to form a series of 55 knuckles adapted to coöperate with each other, and a pintle extending through said knuckles.

2. A hinge made of sheets of laminated wood veneer each folded so as to form two

Copies of this patent may be obtained for five cents each, by addressing the "Commissioner of Patents, Washington, D. C."

leaves connected by a semi-cylindrical member, sections of said semi-cylindrical members being removed to form a series of knuckles adapted to coöperate with each other, a pintle extending through said knuckles, and bearing blocks arranged between each pair of leaves and forming seats engaging the pintle on at least one side.

3. A hinge comprising two sheets of resilient material each folded to form double leaves joined by a semi-cylindrical member, 70 sections being removed from said semi-cylindrical members to form coöperating hinge knuckles, a pintle extending through said knuckles, the free ends of the leaves formed by the removal of sections of each 75 semi-cylindrical member terminating approximately in a plane at right angles to the corresponding leaves and containing the axis of the semi-cylindrical member, each leaf being slit for a short distance at right 80 angles to said free edges in proximity to the ends of the hinge knuckles.

4. A hinge made of two sheets of laminated wood veneer each folded so as to form two leaves joined by a semi-cylindrical member, 85 each semi-cylindrical member having sections removed at intervals to form hinge knuckles, the excisions extending approximately in a plane at right angles to the corresponding leaves and containing the axis 90 of the corresponding semi-cylindrical member, and each leaf being slitted for a short distance at the ends of the knuckles so that the portions of each leaf lying between adjacent knuckles are in the form of tongues 95 each adapted to rest upon an opposed knuckle or that part of the hinge leaf lying in the vicinity of the knuckle depending upon the angular position of the hinge.

5. A hinge comprising two leaves having 100 coöperating hinge knuckles, the thickness of the leaves being substantially equal to the thickness of the knuckles, and each leaf having yieldable elements overlying and closing the gaps between it and the knuckles on the 105 other leaf so as to provide the hinge with substantially smooth continuous surfaces on both sides thereof.

6. A hinge composed of two leaves having 110 coöperating knuckles whose diameter is approximately equal to the thickness of the leaves, each leaf having resilient flaps or ears extending approximately to the medial line of the hinge on each side of each of the knuckles of the other leaf.

In testimony whereof I sign this specification.

HENRY L. HASKELL.
